Primary Examiner — Justin M Jonaitis*Assistant Examiner* — Grace Doyle(74) Attorney, Agent, or Firm — Woodard, Emhardt, Henry, Reeves & Wagner, LLP(57) CLAIM

The ornamental design for a combined planter and wind chimes, as shown and described.

DESCRIPTION

FIG. 1 is a front view of a combined planter and wind chimes, showing my new design;

FIG. 2 is a back view thereof;

FIG. 3 is a left view thereof;

FIG. 4 is a right view thereof;

FIG. 5 is a top view thereof; and,

FIG. 6 is a bottom view thereof.

The portions of the combined planter and wind chimes shown in broken line form no part of the claimed design.
